UNITED STATES PATENT OFFICE.

JOHN E. STRIETELMEIER, OF CINCINNATI, OHIO, ASSIGNOR TO THE IDEAL WHEEL COMPANY, OF CINCINNATI, OHIO, A CORPORATION OF OHIO.

DESIGN FOR A WHEEL.

45,844.

Specification for Design.

Patented May 26, 1914.

Application filed November 21, 1911. Serial No. 661,605. Term of patent 14 years.

To all whom it may concern:

Be it known that I, JOHN E. STRIETELMEIER, a citizen of the United States, residing at Cincinnati, in the county of Hamilton and State of Ohio, have invented a new, original, and ornamental Design for Wheels, of which the following is a specification, reference being had to the accompanying drawing, forming part thereof.

The figure is a side elevation of a wheel, showing my new design.

I claim:

The ornamental design for a wheel, as shown.

JOHN E. STRIETELMEIER.

Witnesses:

JAMES N. RAMSEY,
GOLDIE GORDON.
